[57] CLAIM

The ornamental design for an electronic measuring-/monitoring instrument, as shown and described.

DESCRIPTION

FIG. 1 is a top, front and right side isometric view of an electronic measuring/monitoring instrument showing our new design;

FIG. 2 is a front elevational view thereof;

FIG. 3 is a top plan view thereof;

FIG. 4 is a right side elevational view thereof, the undisclosed opposite side being a mirror image;

FIG. 5 is a rear elevational view thereof; and,

FIG. 6 is a bottom plan view thereof.
